UNITED STATES PATENT OFFICE.

FRANK N. STANLEY, OF MAPLEWOOD, NEW JERSEY.

NAP-RESTORING DEVICE.

Application filed January 24, 1922. Serial No. 531,455.

To all whom it may concern:

Be it known that I, FRANK N. STANLEY, a citizen of the United States, residing in Maplewood, county of Orange, and State 5 of New Jersey, have invented certain new and useful Improvements in Nap-Restoring Devices, of which the following is a specification.

This invention relates to methods of and 10 means for restoring nap on worn or shiny parts of clothing and has for its primary object to provide a handle tool of convenient size capable of use for this purpose.

A good understanding of the invention 15 may be had from the following description of one manner of performing the same, with particular reference to a certain specific form of embodiment of the invention illustrated in the accompanying drawing, in 20 which:

Figure 1 is a view partly in cross section, showing the device in elevation;

Figure 2 is a bottom plan view of Figure 1;

Figure 3 is a detail view of part of Figure 1; and

Figure 4 is a perspective view illustrating the preferred manner of use of the device.

Similar characters of reference designate 30 similar parts in each of the several views.

The tool illustrated in the drawing consists of a handle 1 of convenient shape secured to a base 2 and extending from the upper surface thereof. In its lower face the 35 base is recessed, as indicated at 3, to receive a rectangular piece of card-clothing 4, this material being secured in the recess in any suitable manner, as by means of adhesive. The card-clothing is of a type well known in 40 the art and consists of wire bristles 5 embedded in a heavy but flexible base material 6 of textile or leather and provided with a facing material 7, which may be felt.

An important feature of the present invention is that the steel bristles of the card-clothing are curved in shape, substantially as illustrated. By virtue of this feature a very efficient action of the tool is secured, as will be shown by the following description 50 of the manner of use.

In Figure 4 is illustrated the end of a coat sleeve 8, the material of which has lost its nap adjacent the end of the sleeve, as illustrated at 9, owing to prolonged wear. These 55 portions of the material, therefore, have ac-

quired a shiny or glossy appearance which is particularly noticeable in contrast to the unworn parts of the sleeve on which the original nap is still preserved. To restore the nap in the worn places, the user merely takes 60 the tool of the present invention and presses the same lightly against the cloth. The wire bristles are thus caused to enter the cloth a slight distance. The operator thereupon lifts the tool off the cloth, but in so 65 doing pulls the handle sideways in the direction in which the teeth are pointed. The tool is thus lifted off at an acute angle of approximately 45° to the surface of the cloth. The effect of this action is to cause 70 the teeth to enter the cloth slightly further and to pull the short fibres of the material upwardly so that the ends thereof extend a short distance above the surface of the cloth and thus constitute a new nap 75 thereon. This action is rapidly repeated over the entire worn surface of the cloth, causing the same to be restored to practically the original appearance. By simple procedure, therefore, the shiny spots of clothing 80 may be readily removed and the appearance of the cloth improved considerably.

Although I have herein shown and described only one specific form of embodiment of the invention, it will be readily understood 85 that many changes and modifications may be made therein within the spirit and scope of the following claim without departing from the spirit and scope of the invention, it being my intention to claim the same broadly 90 in whatever form its principles may be employed.

What I claim is:

In a tool for restoring nap on worn textile materials, the combination with a rectangular base having a similarly shaped flat-bottom recess in its under face surrounded by a downwardly extending rim having the entire depth of its inner walls substantially at right angles to the bottom of the recess, 95 of a rectangular strip of card-clothing having its backing material fitted and embedded in the recess of the base and provided with bristles projecting beyond the rim, and a handle projecting from the upper face of 100 said base, whereby the tool may be applied to textile materials.

In testimony whereof I have affixed my signature to this specification.

FRANK N. STANLEY.
